UNITED STATES PATENT OFFICE.

WILLIAM K. SMITH, OF PHILADELPHIA, PENNSYLVANIA, ASSIGNOR TO
WILLIAM T. SMITH & SON, INC., OF PHILADELPHIA, PENNSYLVANIA,
AND CAMDEN, NEW JERSEY, A CORPORATION OF NEW JERSEY.

DESIGN FOR A WOVEN FABRIC.

No. 38,693.

Specification for Design.

Patented July 16, 1907.

Application filed June 17, 1907. Serial No. 379,520. Term of patent 7 years.

To all whom it may concern:

Be it known that I, WILLIAM K. SMITH, a citizen of the United States, residing in Philadelphia, Pennsylvania, have invented a new, original, and ornamental Design for Woven Fabric, of which the following is a specification.

The figure in the accompanying drawing is a face view of a piece of woven fabric showing my new design.

I claim:
The ornamental design for a woven fabric, as shown.

WILLIAM K. SMITH.
